UNITED STATES PATENT OFFICE

145,442

DESIGN FOR A FLAME FAILURE CONTROL UNIT

James C. Hamilton, Lexington, Mass.

Application June 20, 1945, Serial No. 120,210

Term of patent 14 years

(Cl. D81—1)

To all whom it may concern:

Be it known that I, James C. Hamilton, a citizen of the United States of America, residing at Lexington, in the county of Middlesex and Commonwealth of Massachusetts, have invented a new, original, and ornamental Design for a Flame Failure Control Unit, of which the following is a specification, reference being had to the accompanying drawings, forming a part thereof.

Fig. 1 is a perspective view of a flame failure control unit showing my new design.

Fig. 2 is a side elevational view.

Fig. 3 is a cross-section taken on line 3—3 of Fig. 2, and

Fig. 4 is another cross-section taken on line 4—4 of Fig. 2.

The left side of the unit is similar except for the reversed position of the shutters, shown in Figs. 3 and 4.

I claim:

The ornamental design for a flame failure control unit, substantially as shown and described.

JAMES C. HAMILTON.
